SPRING CUSHION

John M. Caughey, Adrian, Mich., assignor to
 Stubnitz-Greene Spring Corporation, Adrian,
 Mich., a corporation of Michigan

Application October 13, 1937, Serial No. 168,717

6 Claims. (Cl. 155—180)

This invention relates to a spring cushion.

This invention particularly concerns the securing together of the bottom plate, the unit spring assembly and bottom frame of a spring cushion and relates to a novel clip which not only secures these members together but also serves as a support for the peripheral portions of the bottom plate.

In the drawing:

10 Fig. 1 is a top plan view of a spring cushion with parts broken away to show the various members of the spring cushion assembly.

Fig. 2 is a section along the line 2—2 of Fig. 1.

Fig. 3 is an enlarged detail vertical section 15 through the bottom frame showing the clip in elevation before the clip has been bent down to secure the bottom frame, bottom plate and unit spring assembly together.

Fig. 4 is an enlarged detail similar to Fig. 3 20 but showing the clip in final position securing the bottom frame, bottom plate and unit spring assembly together.

Figs. 5 and 6 are vertical sections through the frame showing modified forms of the clip assembly.

Referring more particularly to the drawing the spring cushion assembly comprises a bottom frame 1 defining an opening 2, a bottom closure plate 3 which closes the opening 2, a unit spring assembly generally designated 4, and a cover 5 of trimming fabric, leather, or other suitable material for concealing the spring assembly and frame. The spring assembly 4 is assembled as a unit in the well-known manner before it is mounted upon the bottom plate and frame.

The unit spring assembly 4 comprises a plurality of coil springs 6 which have their top convolutions connected together by the usual cross stay wires 7. The bottom walls of the springs 40 are connected by the metal strips 8 of channel cross section which are clamped on to the bottom convolutions of the springs. The unit spring assembly 4 is also provided with the usual top frame 9 which is connected to the outside coil springs 6 of the assembly. This unit spring assembly is old and well-known in the art.

The bottom plate 3 is preferably made from fiber board and has a slightly smaller perimeter than the inside perimeter of the frame 1 so that 50 it can fit within the frame 1. The sheet metal frame 1 preferably is of J cross section. The lower inside edge of the frame 1 is provided with an inwardly turned lip 10. The opening defined by the frame 1 is bridged by the spaced slats 11 55 which are fixed at each end to the frame.

The bottom closure plate 3 rests upon, and is supported by, the spaced slats 11. It is proposed to use a plurality of clip members not only for supporting certain portions of the plate 3 but also for securing the plate 3, bottom frame 1 and 5 unit spring assembly 4 together.

This clip is generally referenced 12 and is shown in section in Fig. 3. The clip 12 is made from an initially flat strip of metal having a lower portion 13 of J section which corresponds 10 in shape and fits within the J frame 1 and is retained against vertical upward movement by the overhanging lip 10. The clip 12 has an intermediate return bent portion 14 which serves as a seat upon which the plate 3 rests and is supported. The clips 12 are inserted in the sides 15 of the J frame 1 between the slats 11 and along the ends 16 which run parallel to the outer slats 11. It is evident that the portions of the plate 3 along the end 16 of the frame are supported 20 along the edge by the clips 12 and the portions of the plate 3 along the sides 15 and between the slats 11 are also supported along the edge by clips 12.

Since the J frame 1 preferably is initially 25 formed with the inwardly turned lip 10, to interengage the clip 12 with the frame 1, the end 17 of the clip 12 is first inserted behind the lip 10 of the frame 1 and the clip thereafter tilted or swung into the position shown in Fig. 3 so that it is 30 nested within the J frame 1 and the interengagement of the end 17 of the clip and the inwardly turned lip 10 of the frame prevents the clip 12 from being drawn vertically upwardly of the frame. 35

After the clips 12 have been inserted in the frame 1, the bottom plate 3 is then positioned upon the slats 11 and the seats 14. The unit spring assembly 4 is next positioned upon the bottom plate 3 and thereafter the upper end 18 of 40 each clip 12 is turned inwardly of the frame 1 and downwardly toward the seat 14 which securely clamps the plate 3 and unit spring assembly 4 against the seat 14. Thereafter the cover 5 is applied to the spring cushion assembly 45 and frame 1 in any well-known manner.

A modified form of the bottom frame is shown in Fig. 5. Here the bottom frame 20 is of J section but the inwardly turned bead 10 is omitted. Therefore in this construction the clip 12 is 50 welded to the frame 20 at 21. Except for these differences the bottom plate 3, unit spring assembly and frame are secured together by the clip 12 in the same fashion as above described.

In Fig. 6 the bottom frame 20 is of J section 55

the same as that shown in Fig. 5. In this form of the invention the clip 22 comprises a strip of metal in the form of an L which is welded to the frame 20 as at 23. The shorter leg 24 of the 5 clip serves as a seat for the bottom plate 3 in a fashion similar to the seat 14 of the principal form of the invention. The longer leg 25, similarly to the portion 18 of the clip 12, is turned downwardly over the unit spring assembly thus 10 clamping the spring assembly and bottom plate 3 together and between the bent down leg 25 and the seat 24.

I claim:

1. A spring cushion comprising a bottom frame 15 defining an opening, spaced cross slats bridging said opening and fixed at each end to said frame, a bottom plate resting upon and supported by said spaced slats, a spring unit mounted upon said bottom plate, and one or more clips secured to 20 the said bottom frame member each comprising a portion extending inwardly of the frame beneath the bottom plate forming a seat for supporting the same and a portion extending upwardly about the edge of the bottom plate and 25 unit spring assembly and then inwardly to secure the bottom plate and spring unit together and to said bottom frame.

2. A spring cushion comprising a bottom frame defining an opening, spaced cross slats bridging 30 said opening and fixed at each end to said frame, a bottom plate resting upon and supported by said spaced slats, a spring unit mounted upon said bottom plate, and one or more spring clips each comprising a strip of sheet metal secured to 35 the said bottom frame member and having a portion extending horizontally inwardly of the frame beneath the bottom plate to form a seat for supporting the bottom plate along an edge and a portion extending upwardly about the edge 40 of the bottom plate and unit spring assembly and bent inwardly and overlapping the said bottom plate and unit spring assembly to secure the same together and to said bottom frame.

3. A spring cushion comprising a bottom frame 45 defining an opening, spaced cross slats bridging said opening and fixed at each end to said frame, a bottom plate resting upon and supported by said spaced slats, a spring unit mounted upon said bottom plate, and one or more clips secured to 50 the said bottom frame member each comprising a bottom portion corresponding in shape and fitted within the bottom portion of the bottom frame member and an intermediate portion extending inwardly of the frame member beneath 55 the bottom plate to form a seat for supporting the bottom plate and an upper portion extending about the edge of the bottom plate and unit spring assembly and then inwardly to clamp the edge portion of the bottom plate and unit spring 60 assembly against the seat whereby the unit spring assembly and bottom plate are secured together and to said bottom frame.

4. A spring cushion comprising a bottom frame having an upstanding wall defining an opening, spaced cross slats bridging said opening and fixed at each end to said frame, a bottom plate resting upon and supported by said spaced slats, 5 a spring unit mounted upon said bottom plate, and one or more clips secured to the upstanding wall of the bottom frame member each comprising a strip of metal having a portion extending inwardly substantially perpendicular to the 10 upstanding wall of the frame member and beneath the bottom plate forming a seat for the same and a portion extending upwardly about the edge of the bottom plate and the lower edge 15 of the unit spring assembly and then inwardly to clamp the bottom plate and spring assembly against said seat.

5. A spring cushion comprising a bottom frame having an upstanding wall defining an opening, the said bottom frame having a lower edge portion 20 extending inwardly, upwardly and then outwardly to form an overhanging lip, spaced cross slats bridging said bottom frame opening and fixed at each end to said frame, a bottom plate resting upon and supported by said slats above 25 the inwardly turned bottom edge of the said frame, a spring unit mounted upon said bottom plate, and one or more clips having a bottom portion turned inwardly and upwardly and positioned within the said bottom frame member 30 and beneath the inwardly turned lip, and an intermediate portion extending inwardly of the said frame and then outwardly to form a seat for the bottom plate and an upper portion extending along the edge of the bottom plate and unit 35 spring assembly and then inwardly to clamp the bottom plate and spring assembly against said seat.

6. A spring cushion comprising a bottom frame of J cross section defining an opening, the lower 40 edge of the J section having a lip turned outwardly of the frame member and overhanging the U channel formed by the lower portion of the J section, spaced across slats bridging said bottom frame opening and fixed at each end to said 45 frame, a bottom plate resting upon and supported by said slats above the inwardly turned bottom edge of the said frame, a spring unit mounted upon said bottom plate, and one or more clips having a bottom portion turned inwardly and 50 upwardly and positioned within the said U portion of the J section and beneath the inwardly turned lip and an intermediate portion extending inwardly of the said frame and then outwardly to form a seat for the bottom plate and an upper portion extending along the edge of the bottom plate and unit spring assembly and then 55 inwardly to clamp the bottom plate and spring assembly against said seat.

JOHN M. CAUGHEY.
